UNITED STATES PATENT OFFICE

PAUL F. SHIVERS, OF WABASH, INDIANA, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

FUEL-BURNER-CONTROL SYSTEM

Application filed May 3, 1926. Serial No. 106,274.

In the installation of oil burners, especially those of the household type where constant attention is not possible, it is necessary to provide means by which the flow of fuel will be automatically cut off either in case of failure of initial ignition, or in case of failure of combustion, or in case the operator attempts to render portions of the apparatus inoperative.

The object of my present invention is, therefore, to provide a simple and efficient mechanism by which the above-stated desirable results may be attained.

The accompanying drawings illustrate my invention. Fig. 1 is a diagrammatic illustration of an embodiment of my invention; and Fig. 2 is a diagram of a modification.

In the drawings 10 indicates a fuel burner and 11 an electrically actuated controller by means of which delivery of fuel to burner 10 is controlled. The burner 10 and controller 11 will, of course, be of a type suitable to handle the desired fuel, the details forming no part of my invention except that the controller 11 is electrically actuated. This element 11 may, as will be readily apparent, be a motor driving a fuel pump delivery to the burner, or an actuator for a valve which will control delivery of a fuel to the burner, etc.

A circuit breaker 12, of a type to be influenced by the presence or absence of combustion at burner 10, comprises terminals 13 and 14. This element 12 may conveniently be a thermostat of ordinary form or may be an element responding to variations in light or pressure induced by combustion conditions.

A most satisfactory element for this purpose is the thermostat shown in my pending application, Serial No. 70,808 filed November 23, 1925, in which making or breaking of the circuit is accomplished promptly upon reversal of temperature conditions irrespective of the range of temperature variations.

A circuit breaker 15, conveniently a one point thermostat, comprising terminal 16 and a temperature responsive cooperating terminal 17, is arranged in the room to be heated.

An electro-magnetic switch-actuating mo-

tor 18 is capable of actuating a switch 19. This actuating motor and its switch may vary considerably as to form and construction but must be capable of being stalled without injury to its circuits. In the diagram the motor is of the shaded-pole induction type, without contact brushes or cutouts and comprises the shaded-poles 20, rotor 21 and pole windings 22 and therefore is capable of being stalled without injury.

Geared to rotor 20 is a plunger 23 biased in one direction by a spring 24 capable of reversely rotating the rotor in the absence of current in the field coils. Plunger 23 actuates two snap-switch elements 25 and 26. Element 25 may make or break connection between two terminals 27 and 28. Element 26 may alternately make or break connection between the two pairs of terminals 29, 30 and 31, 32.

A delayed-action relay 33, comprising two cooperating terminals 34 and 35 which are biased open and are normally held in contact by the thermal element 36 arranged within the influence of an electric heating coil 37.

In order that the elements 15 and 18 may be low-voltage elements, I provide a transformer 40 comprising a primary winding 41 and a secondary winding 42.

The electrical connections are as follows: wire 51 from 16 to 42; wire 52 from 42 to a wire 53 connecting 31 and 37; wire 54 and 37 to a wire 55 connecting one end of coils 22 with 13; wire 56 from 14 to 30 and 32; wire 57 from 17 to coil 22; wire 58 from wire 57 to 29; wire 59 from 35 to 27; wire 60 from 11 to line; and wire 61 from 60 to 41.

Thus far the connections are the same in Figs. 1 and 2. In Fig. 1 the further connections are: wire 62 from 28 to 11; wire 63 from 41 to 59 and wire 64 from 34 to line.

In Fig. 2 the further connections are: wire 62' from 28 to line; wire 63' from 41 to line and wire 64' from 34 to 11.

The difference between Figs. 1 and 2 is that in Fig. 1 terminals 34 and 35 control both elements 11 and 18, while in Fig. 2 terminals 34 and 35 are in circuit only with 11.

For convenience in further description 100

and in the claims element 11 will be called the fuel controller; element 12 the circuit-breaker responsive to combustion conditions of the burner; element 15 the room thermostat or remote control switch; element 18 the switch actuator; element 25-27-28 the fuel controller switch; element 26-29-30 the safety switch; thermal element 33-34-35-36-37 the delayed-action relay; and element 10 40-41-42 the transformer.

It will be understood that the delayed-action relay may be of any construction such that a flow of current in its circuit, if and when maintained for a sufficient time and of 15 sufficient volume, will cause attainment of an abnormal circuit relation.

Referring now to Fig. 1, the operation will be as follows, the parts being, as shown, in the warm position, where no action of the 20 burner is desired.

A potential exists in the circuit line, 60, 61, 41, 63, 59, 35, 34, 64, line.

Upon a cooling of the room thermostat a circuit 16, 51, 42, 52, 53, 37, 54, 55, 22, 57, 25 17, 16 is established and rotor 21 moves to shift the fuel controller switch 25 into contact with terminals 27, 28 and the safety switch 26 into contact with terminals 31, 32. Switch 25 establishes the circuit, line, 64, 34, 30 35, 59, 27, 25, 28, 62, 11, 60 and line, thus actuating the fuel controller 11 so that there will be fuel delivery to burner 10.

The flow of current through 37 causes a heating of the thermal element 36 which, in 35 time, will cause a separation of terminals 34 and 35, if there has been a failure of ignition and the combustion indicator has not been warmed sufficiently to close contacts 13, 14. An actuation of the delayed-action relay breaks the energizing circuit for the fuel controller 11 and also breaks the primary circuit of the transformer thus de-energizing the field of the switch actuator and permitting spring 24 to reverse the switch 40 25 and thus break the circuit of the fuel controller at a second point 27-28. Under such circumstances fuel delivery may not be resumed until the delayed-action relay has been reset by placing element 36 in position 45 to hold terminals 34 and 35 in contact.

In Fig. 2 the primary coil 40 of the transformer, is always energized and the separation of terminals 34 and 35 directly breaks the circuit of the fuel controller 11, switch 55, 25 remaining in position bridging terminals 27, 28.

If initial ignition has occurred in proper time terminals 13 and 14 will be caused to contact whereupon circuit is established 60 through 31 and 32 to short out the heater 37 as follows: 14, 56, 32, 26, 31, 53, 52, 42, 51, 16, 17, 57, 22, 55, 13, 14, thus maintaining current in the switch actuator and thus maintaining the circuit of the fuel controller 65 through switch 25.

Whenever the remote control switch (room thermostat) opens the break at 16, 17 releases the rotor 21 and permits spring 24 to break the circuit of the fuel controller by moving switch 25 into the position shown. 70

In case of a failure of combustion at any time (as distinguished from failure of ignition) a circuit break occurs at 13-14, thus breaking the shunt circuit around the heating element 37, which, after a suitable period, will flex the thermal element 36 to permit the contact points 34-35 to separate, breaking the burner motor circuit. 75

Some operators or users are inclined to attempt to eliminate the circuit breaker 12 from the system by placing a short across terminals 13-14, but in my present device any such attempt serves, upon a closing of the room thermostat, to immediately cause a break in the fuel controller circuit at 34-35 80 in the following manner. Switch 26 being in its normal position bridging contacts 29, 30, a connection between wires 55 and 56 establishes circuit 16, 51, 42, 52, 53, 37, 55, 56, 30, 26, 29, 58, 57, 17, 16, thereby short-circuiting coils 22, so that the entire secondary current is delivered through the heater 37 causing it to be heated very quickly, resulting in a break at 34-35 and requiring manual re-establishment of contact between 34 85 and 35. 90

If contacts 13 and 14 should be permanently connected or shorted while the burner was working there would, at first, be no action but, when the room thermostat warmed up so as to cause a break at 16-17 there would result a break in the fuel controller circuit at 27-28, in the manner already described. 100

Then, when the room thermostat cooled down and reestablished contact at 16-17 the full secondary current would be delivered through the heater 37, as already described, and the safety break at 34-35 would promptly occur. 105

It will of course be readily understood that an automatic ignition device may be readily provided either of such character as to give a continuous spark throughout the entire period of operation or such as to be automatically cut out as soon as the burner has started. For instance, in Fig. 1, I show a circuit breaker 70 comprising a pair of normally contacting thermostatic terminals which will separate when heated and which may be arranged within the influence of the combustion conditions of the burner. These terminals may be connected by circuit wires 71 with the motor feed lines 60 and 62 and with the sparking element 72. 115 120

I claim as my invention:

1. In a control system for fuel burners, a burner, a main electric motor controlling operation of said burner, an energizing circuit for said motor, a switch-actuating electric 125

motor, a reciprocating switch-actuating member controlling the starting and stopping of said main motor actuated in one direction by said switch-actuating electric motor, biasing means acting constantly on said member in opposition to said switch-actuating motor, a circuit for said switch-actuating motor, a thermal circuit breaker in the main motor circuit and comprising an electric heating element in series in the circuit of the switch-actuating motor, a remote switch in circuit with said heating element, switching means in circuit with said remote switch and controlled by combustion conditions adjacent the burner, and means for varying the effect of said switching means on said heating element.

2. The combination with a fuel burner and electrically actuated fuel supplying means therefor, of an electric motor, an energizing circuit therefor, a switch for controlling said circuit, an electric actuating element in series with said motor in said circuit, a timing switch operable thereby and connected to break the energizing circuit for said fuel supplying means, a reciprocable element actuated in one direction by said motor and constantly biased for movement in the opposite direction, switching means controlled by combustion conditions adjacent the burner, and means controlled by said reciprocable element for varying the effect of said switching means on said electric actuating element.

3. In a control system for fuel burners, a burner motor, an energizing circuit therefor including a switch and a delayed action circuit breaker, a transformer having its primary in series with the circuit breaker, a room thermostat in series with the secondary of the transformer, a supplemental electric motor having its energizing circuit connected to the room thermostat and transformer secondary, an electric actuating element for said circuit breaker, electric connections between the actuating element and the supplemental motor circuit, a combustion controlled circuit breaker arranged to shunt the actuating element in the presence of combustion, a safety switch, and means actuated by said supplemental motor to shift the burner switch and to shift the safety switch for varying the effect of said combustion controlled circuit breaker on said actuating element.

4. In a control system for fuel burners, a burner motor circuit including a switch and a delayed action circuit-breaker comprising an electric heating element, a transformer, a room thermostat in series with the secondary of the transformer, a supplemental electric motor having its energizing circuit connected to the room thermostat and transformer secondary, electric connections between the heating element and the supplemental motor circuit, a combustion-controlled circuit-

breaker arranged to shunt the heating element in the presence of combustion, a two-position safety switch in circuit in either position with the heating element and combustion-controlled circuit-breaker and shorting the supplemental motor in an abnormal closed condition of said combustion controlled circuit-breaker, and means actuated by said supplemental motor to shift the burner switch and safety switch.

5. In a control system for fuel burners, a burner motor circuit including a switch and a delayed-action circuit-breaker comprising an electric heating element, a transformer having its primary in series with the circuit-breaker, a room thermostat in series with the secondary of the transformer, a supplemental electric motor having its energizing circuit connected to the room thermostat and transformer secondary, electric connections between the heating element and the supplemental motor circuit, a combustion-controlled circuit-breaker arranged to shunt the heating element in the presence of combustion, a two-position safety switch in circuit in either position with the heating element and combustion-controlled circuit-breaker and shorting the supplemental motor in an abnormal closed condition of said circuit-breaker, and means actuated by said supplemental motor to shift the burner switch and safety switch.

6. In a control system for fuel burners, the combination of a high voltage circuit, a low voltage circuit, a motor in the high voltage circuit for controlling the operation of the burner, a switch actuating electric motor in the low voltage circuit, a switch member operated by said switch-actuating motor for controlling the starting and stopping of the burner motor, a circuit-breaker in the high voltage circuit and comprising a thermostatic element and a heater therefor in the low voltage circuit, a circuit breaker in the low voltage circuit of the switch-actuating motor, and arranged to shunt said heater under certain conditions, and means connected in said low voltage circuit and operable, under certain conditions, to cause said last mentioned circuit-breaker to shunt said actuating motor, and a switch to open and close the low voltage circuit.

7. In a control system for fuel burners, a burner-motor circuit comprising a fuel-controlling motor, a heat-affected circuit-breaker, and a controlling switch; a low voltage circuit comprising in series, an electrically-actuated switch motor for actuating said switch, an electric heater for the said circuit-breaker, and a room thermostat; a normally-open heat-affected circuit-breaker to be arranged within the immediate heat-effect of the burner; a switch terminal connected to a first contact of said last-mentioned circuit breaker, a cooperating switch terminal connected to one terminal of said switch motor

and to said room thermostat in parallel, switch means effective, when said switch motor is deenergized to connect said two switch terminals, the second contact of said last-mentioned circuit breaker being connected to said low-voltage circuit between said heater and motor, whereby if said last-mentioned circuit breaker is open, a circuit is established through said switch motor and said heating element under the control of said thermostat, and if said last-mentioned circuit breaker is closed, a circuit is established around said motor and through said heating element under the control of said thermostat; a third switch terminal connected to said first contact of said last mentioned circuit breaker and a cooperating switch terminal connected to the other terminal of said switch motor through said heating element, said last-mentioned switch means being effective, when said switch motor is energized, to connect said two last-mentioned switch terminals whereby, if said last-mentioned circuit breaker is open, a circuit is established through said motor and said heating element under the control of the room thermostat, and if said last-mentioned circuit breaker is closed, a circuit is established around said heating element and through said motor under the control of said room thermostat.

8. In a control system for fuel burners, a high voltage burner-motor circuit comprising a fuel-controlling motor, a heat-affected circuit breaker, and a controlling switch; an electrically controlled switch motor for actuating said switch; and a low-voltage circuit comprising a cold-open room thermostat, cold-open heat affected circuit breaker to be arranged within the immediate heat effect of the burner, an electric heater for the first mentioned circuit breaker, the energizing circuit of the switch motor, and a two-position switch actuated by the switch motor, said two-position switch in non-fuel-delivery position of the switch motor affording a circuit for the heater through the second mentioned circuit breaker which will shunt the switch-motor relative to the heater and in the fuel delivery position of the switch-motor, affording a circuit through the second mentioned circuit breaker which will shunt the heater relative to the switch-motor.

9. In a control system for fuel burners, a burner motor, a circuit therefor including a switch and a delayed-action circuit breaker, an electric heating element for said circuit breaker, a transformer having its primary in series with the circuit breaker only, a room thermostat in series with the secondary of the transformer, a supplemental electric motor for actuating said switch having its energizing circuit connected in series to the room thermostat, transformer secondary, and the heating element a combustion

controlled circuit breaker normally open when there is no combustion, switching means actuated by said supplemental motor, and means so interconnecting the same with the heater, combustion controlled circuit breaker and supplemental motor that, when the supplemental motor is energized operative closing of the combustion controlled circuit breaker shunts the heater only and, when the supplemental motor is deenergized, operative closing of the combustion controlled circuit breaker short circuits the supplemental motor only.

10. Burner control mechanism comprising electrically operated fuel supplying means; a circuit including said means and including a delayed action circuit breaker and a main switch; a second circuit including a motor for operating the main switch and an electrically operated actuator for said delayed action circuit breaker in series, a burner switch responsive to temperature conditions adjacent the burner, switch means operable by said motor, and means so interconnecting the elements of the second circuit that the positions of said last mentioned switch means and said burner switch upon energization of said second circuit determine the rate of current flow through said electrically operated actuator.

11. Burner control mechanism comprising electrically operated fuel supplying means; a circuit including said means and including a delayed action circuit breaker and a main switch; a second circuit including a thermostatically operated switch, a motor for operating the main switch, and an electrically operated actuator for said delayed action circuit breaker in series, and a switch responsive to temperature conditions adjacent the burner; a third switch normally shiftable in response to the position of said thermostatically operated switch, and means so interconnecting the elements of said second circuit that the operative condition of said burner-affected switch at the time of closure of said thermostatic switch determines the rate of current flow through said electrically operated actuator.

12. Burner control mechanism comprising electrically operated fuel-supplying means; a circuit including said means and including a delayed-action circuit breaker and a main switch; a second circuit including a motor for operating the main switch and an electrically operated actuator for said delayed-action circuit breaker in series, a switch responsive to temperature conditions adjacent the burner, means operable by said switch actuating motor and means interconnecting the elements of said second circuit to cause closure of said last mentioned switch to shunt said actuator when said main switch is closed and to shunt said switch operating motor when said main switch is open.

13. Burner control mechanism comprising a burner; a main circuit including electrically operated means for supplying fuel to said burner, a circuit breaker and a circuit controller; a second circuit normally in control of said main circuit through said controller; means for opening and closing said second circuit, an electric actuator connected in said second circuit and operable, upon energization, to open said circuit breaker, means responsive to temperature conditions adjacent said burner for shunting said actuator, and means so connected in the second circuit that operative closure of said burner responsive means in advance of energization of said second circuit to energize said main circuit will render said burner responsive means ineffective to shunt said actuator. 70
14. Burner control mechanism comprising a main circuit including electrically operated fuel-supplying means, a delayed action circuit breaker, and a main switch; a room thermostat; a second circuit under the control of said thermostat and including a motor for actuating said main switch and an actuator for said delayed-action circuit breaker in series therewith; a switch positioned to be affected by conditions adjacent said burner; means controlled by said switch actuating motor and means so connecting said last mentioned switch and last named means in said second circuit that said last named means alternately connects said last mentioned switch to shunt said actuator and to shunt said switch actuating motor. 80
15. In a burner control, a two-position switch continuously biased to one of its circuit closing positions, a switch responsive to combustion conditions in series with said two position switch in each of its positions, a switch actuating electric motor acting, when sufficiently energized, to shift said two-position switch to its other circuit closing position, a switch responsive to temperature conditions at a remote point closed when cold, electric fuel supplying means, a circuit breaker, an electrically operated actuator for opening said circuit breaker, an energizing circuit for the fuel supplying means including said circuit breaker and a main switch operable by said switch actuating motor, and circuit connections including the remote switch, the actuator, the switch actuating motor, the two-position switch, and the combustion controlled switch, whereby closure of the remote switch subsequent to an operative closure of the combustion controlled switch will energize the actuator without operatively energizing the switch actuating motor. 85
16. In a control system for fuel burners, a burner, electrically operated means controlling operation of said burner, an energizing circuit for said means, a switch actuating electric motor, a switch in said energizing circuit under the influence of said motor in clos- 90
- ing direction and continuously biased in opening direction, a combustion controlled switch responsive to combustion conditions of the burner open when cold, a two-position switch in series with said combustion controlled switch under the influence of the switch actuating motor to one of its circuit closing positions and continuously biased toward its other circuit closing position, a circuit breaker in said energizing circuit, an electric actuator acting when energized to open said breaker, a switch responsive to temperatures at a remote point, and electrical connections between an energy source, the combustion controlled switch, the two-position switch, the remote switch, the actuator, and the switch actuating motor, whereby closure of the remote switch subsequent to an operative closure of the combustion controlled switch will energize the actuator without operatively energizing the switch actuating motor. 95
- In witness whereof, I have hereunto set my hand at Wabash, Indiana, this 30th day of April, A. D. one thousand nine hundred and twenty-six. 100
